UNITED STATES PATENT OFFICE.

JAMES R. BRYANT, OF CRAWFORDSVILLE, INDIANA.

DESIGN FOR A CREST-TILE.

SPECIFICATION forming part of Design No. 22,832, dated October 10, 1893.

Application filed September 9, 1893. Serial No. 485,192. Term of patent 3½ years.

To all whom it may concern:

Be it known that I, JAMES R. BRYANT, a citizen of the United States, residing at Crawfordsville, in the county of Montgomery and 5 State of Indiana, have invented a new and original Design for Crest-Tiles, of which the following is a specification.

The invention relates to a new and original design for crest-tiles.

10 The object of the present invention is to provide an ornamental and attractive crest-tile; and the essential feature resides in a crest-tile having an upper portion provided at the top with angular recesses, with trefoil 15 or clover leaf openings and with circular and diamond-shaped openings, and in a base or apron having angular and curved corrugations.

In the drawings—Figure 1 is a side elevation of a portion of a crest-tile showing my 20 new design. Fig. 2 is an end elevation of the same.

Referring to the drawings, 1 designates the upper portion of a crest-tile provided at its 25 upper edge with a series of tapering angular

openings 2 and having below the same in the intervals between the tapering openings or recesses 2 trefoil or clover-leaf openings 3. The upper portion 1 is also provided with alternately arranged series of diamond-shaped 30 openings 4 and circular openings 5.

The base or apron 6 of the crest-tile is provided with angular corrugations 7 and 8, and curved corrugations 9 and 10. The curved corrugation 9 is approximately semi-cylindrical; and the corrugation 10 is sigmoidally curved.

It will be seen that the crest-tile presents an ornamental and attractive appearance.

What I claim is—

35 The design for a crest-tile herein shown and described.

In testimony that I claim the foregoing as my own I have hereto affixed my signature in the presence of two witnesses.

JAMES R. BRYANT.
